UNITED STATES PATENT OFFICE.

ELEANOR P. ROBERTS, OF LINN GROVE, IOWA.

TATTING-SHUTTLE WINDER.

1,195,501.

Specification of Letters Patent. Patented Aug. 22, 1916.

Application filed June 17, 1915. Serial No. 34,603.

To all whom it may concern:

Be it known that I, ELEANOR P. ROBERTS, a citizen of the United States, residing at Linn Grove, R. F. D., in the county of 5 Buena Vista and State of Iowa, have invented certain new and useful Improvements in Tatting-Shuttle Winders, of which the following is a specification.

My invention relates to tatting shuttle 10 winders, and the objects thereof are to provide a device of this character in which the shuttle is at all times arranged in its proper position and can be easily and quickly removed when the occasion so requires; and to provide a tatting shuttle in 15 which a novel tension device is combined with the shuttle winder *per se*.

To the accomplishment of the recited objects and others coördinate therewith, the 20 preferred embodiment of my invention resides in the construction and arrangement of members shown in the accompanying drawings, hereinafter described and embraced within the scope of the appended 25 claims.

In said drawings Figure 1 is a side elevation of the shuttle winder embodying my invention, a portion of the frame being broken away to more clearly illustrate the 30 detachability of the spring at the top of said frame; Fig. 2 is a transverse sectional view taken along lines 2—2 of Fig. 1; and Fig. 3 is a top plan view of the device.

Generally speaking, my invention comprises a substantially rectangular shaped frame consisting of two duplicate side members joined together at each end by suitable cross bars or rods. Within the upper portion of the frame, considered as an entire, I mount upon the opposite cross bars a pair of yieldable sustaining elements, and coöoperating with said elements is a centrally disposed crank, the principle being that the shuttle may be easily inserted over the crank 40 so as to permit the yieldable elements to exert a slight inward pressure in opposite directions and thereby sustain the shuttle in its proper relations medially of the frame. At the bottom of the frame, and preferably 45 at one corner thereof, I mount a tension device involving a pair of substantially arcuate shaped clamps and a supporting rod, one of the clamps being stationary and the other being movable against the adjustable 50 tension of a coil spring. At the opposite

end of the frame I provide a pair of openings through which the thread may be passed for the purpose of augmenting the tension, if so desired.

Referring more particularly to the drawing for a detailed description of my invention, the numeral 1 designates two duplicate sections involving diagonal braces 2, and joined together at their ends by the upper cross rods 3 and the lower cross rods 4. 60 Running entirely through the upper portion of the frame is a two-piece crank 5 having a handle 6 and provided at its opposite end with a detachable connection as 7. This crank loosely supports a pair of oppositely 65 disposed inwardly bowed spring elements 8, the outer ends of which are provided with slightly elongated slots 9 encompassing the extremities of the upper cross bars 3. Contiguous the central portion of each spring 70 element 8 and also rigidly secured to the inner ends of the crank 5 is a clamp 10 having an inner lining 11.

At the base of the frame 1, and preferably 75 at the lower right hand corner thereof, I 80 mount a pair of oppositely disposed members 12, having curved confronting faces and supported by the cross rod 3. Bearing against one of these members is a coil spring 85 13, the tension of which may be easily regulated by the proper manipulation of a nut 14. To further increase the tension it may be found desirable to provide an arrangement on the opposite side of the frame, and in anticipating this contingency I have provided 90 a pair of small openings 15 having narrow leadways 17 communicating therewith.

In operation the tatting thread is either placed around the little finger or passed 95 through the openings 15, located on the left-hand end of the frame, then downwardly over the adjacent cross bar 4, between the opposing faces of the members 12 and finally secured to the shuttle 16. 100 Upon securing the desired tension by means of screwing or unscrewing the nut 14, and subsequently operating the crank handle 6, it will readily be seen that the tatting will be quickly and properly wound upon the 105 shuttle, thereby saving a great deal of time. After the shuttle has become filled it may be easily removed by simply exerting outward pressure on the clamp members 10, whereupon the yieldable springs will give 110

and such movement will be compensated for by the elongated slots 9 encircling the outer extremities of the upper cross members 3.

I claim:

- 5 1. In a device of the character described, the combination of a frame having a plurality of connecting members, a shuttle clamp comprising a pair of jaws, yieldable elements adapted to normally force said
- 10 jaws toward each other, said elements having elongated slots encircling said connecting members for permitting separation of said elements, a tension device, and means extending through said elements for rotating said jaws.
- 15 2. In a device of the character described,

the combination of a frame having a plurality of connecting members, a shuttle clamp comprising a pair of jaws, a pair of bow springs adapted to normally force said jaws toward each other, said springs having elongated slots encircling said connecting members, a tension device, and means extending through said springs for rotating said jaws.

20 In testimony whereof I affix my signature in the presence of two witnesses.

25 ELEANOR P. ROBERTS.

Witnesses:

OTTO DAW,
Mrs. O. B. SCOTT.
